SLUB COUNTING DEVICE

Frank Nistico, Westfield, and Basil S. Sprague, New Providence, N. J., assignors to Celanese Corporation of America, New York, N. Y., a corporation of Delaware

Application June 5, 1951, Serial No. 229,958

7 Claims. (Cl. 73—160)

This invention relates to a counting device and relates more particularly to a slub detector and counting device for counting slubs and other like physical defects in a running yarn without causing a yarn break during said slub detecting and counting operation.

A slub is a soft, thick, uneven place in a yarn, somewhat knot-like in character and may be caused by the passage of a yarn containing broken filaments through a ring traveler or other device where tension is placed on the yarn. Slubs may also be formed during spinning operations in the production of artificial filamentary materials by extrusion methods. The presence of an excessive number of slubs is quite undesirable and is an indication of poor yarn quality.

An object of this invention is the provision of a slub detector for detecting and keeping an individual count of the slubs encountered in a running yarn.

Another object of this invention is to provide a slub detector and counter mechanism which is operated upon directly and in a positive manner by the presence of a slub in a running yarn without causing a yarn break where said slub appears.

Yet another object of our invention is the provision of a slub detector and counter which is rugged in construction, economical to manufacture and easily operated and read.

Other objects of this invention will appear from the following detailed description and the accompanying drawing.

In the drawing wherein a preferred embodiment of this invention is shown:

Fig. 1 is a plan view of the novel slub detector and counter of our invention;

Fig. 2 is a side elevational view of our novel slub detector and counter showing the yarn guides through which the yarn is run, the slub gate and the counting dial for numerically recording the slubs which are detected;

Fig. 3 is an end view of our novel device, partly in section, taken along the line 3—3 in Fig. 1 in the direction of the arrows;

Fig. 4 is another side elevational view of our novel device, shown partly in section, taken along the line 4—4 in Fig. 1 in the direction of the arrows; and,

Fig. 5 is a detail view of a modified means for spring-loading the slub gate through which the yarn under test is passed.

Like reference numerals indicate like parts throughout the several views of the drawing.

Referring now to the drawing and more particularly to Fig. 1, the yarn which is to be tested for slub count and indicated by reference numeral 1, is threaded through a pigtail guide 2, through the gate 3 of the slub detector assembly or mechanism generally indicated by reference numeral 4, and then through a second pigtail guide 5. The slub detector assembly 4 comprises in its major structural parts a longitudinal U-shaped bracket 6 provided with upstanding arms 7 and 8 and a lateral U-shaped bracket 9 provided with upstanding arms 11 and 12. Brackets 6 and 9 are suitably connected and may be conveniently designed to interlock or to be otherwise assembled together and held in position to form a unitary structure.

Slub gate 3 is slidably mounted in a holder 13 which is provided with a plurality of broad fingers 14 suitably attached to holder 13 as, for example, by means of a spotweld. Fingers 14 are spaced from holder 13 the proper distance to provide a slot sufficiently wide and

deep to permit the introduction of slub gate 3. Integral with slub gate holder 13 is a curved spring pawl 15 and the gate holder 13 itself, at the lower end thereof, is in the form of a bent leg 16. The purpose and function of both pawl 15 and leg 16 will hereinafter be described in detail. The entire structure comprising slub gate holder 13, pawl 15 and leg 16 is mounted so as to be freely rotatable about a shaft 17 which is journaled in arms 11 and 12 of the lateral U-shaped bracket 9.

Fixed to rotatably mounted shaft 17 for rotation therewith is a ratchet wheel 18, mounted in such position adjacent to slub gate holder 13 that the notches 19 in said ratchet wheel register with and are adapted to be engaged by the pawl 15 on slub gate holder 13, as shown in Fig. 4. The slub gate holder 13 on shaft 17 may be adjusted to assume any desired position up to about 45° from the vertical by means of a rotatably adjustable circular stop 21 the position of which is controlled by a set screw 22 provided with a locking nut 23 for holding stop 21 in adjusted position. Slub gate holder 13 is normally held against stop 21 by means of a coil spring 24 which is carried by shaft 17. One leg of coil spring 24 is held in fixed position by the base of U-shaped bracket 6 while the other leg of coil spring 24 engages the rear of slub gate holder 13 to press the same against circular stop 21.

A second stop is provided for limiting the movement of slub gate holder 13 when rotated in the opposite direction. The second stop comprises an adjustable set screw 25 which is threaded through arm 7 of longitudinal U-shaped bracket 6. Set screw 25 is so positioned in relation to leg 16 that, upon the clockwise rotation of slub gate holder 13, as shown in Fig. 2, the limit of movement is reached when leg 16 strikes the end of set screw 25. A lock nut 26 is provided to hold set screw 25 in adjusted position.

To place the novel slub detector and counter of our invention in operation, yarn 1, taken from a suitable yarn supply whose slub count is to be measured, is threaded through pigtail guide 2, slub gate 3 and pigtail guide 5, as shown more particularly in Figs. 1, 2 and 4, and the yarn is then taken up by means of a suitable take-up mechanism (not shown) which causes it to run through said pigtail guide and slub gate.

If yarn 1 contains a slub or thickened portion, as for example that portion identified by reference letter S, which portion has a diameter greater than the width of the slub gate 3, said slub S will not be able to pass through. Accordingly, the thickened portion S will strike slub gate 3 and, since it cannot pass, will cause slub gate holder 13 to be rotated in a clockwise direction, as shown in Fig. 2, against the urging of coil spring 24. The movement of slub gate holder 13 causes ratchet wheel 18 to be rotated since pawl 15 is normally in engagement with a notch 19. The rotation of ratchet wheel 18 causes shaft 17 to be rotated and this movement of shaft 17 actuates an indicator hand 27 which is keyed thereto. Hand 27 cooperates with a numbered chart, generally indicated by reference numeral 28 by means of which a record of the slub count is maintained. After the slub S is running yarn 1 has depressed or rotated slub gate holder 13 to the position shown in dashed lines in Fig. 2, slub S is rejected and rides out over the top of slub gate 3. After the slub S has passed over the top of the slub gate, the yarn which follows then slips down into the slot in the center of slub gate 3 and the slub gate holder 13 is returned to its original position in contact with circular stop 21 by the action of coil spring 24. Movement of ratchet wheel 18 in a counterclockwise direction is prevented by means of a detent 29 mounted on arm 11 of lateral bracket 9 by means of a screw 31. This sequence of movements places all of the elements in position to repeat the cycle if another slub is encountered in the running yarn.

In lieu of employing the coil spring 24 on shaft 17 to return slub gate holder 13 to its usual position during the normal running of the yarn 1, an arrangement such as that shown in Fig. 5 may be employed. In this alternative arrangement, a coil spring 32 is provided, one end of which passes through a hole 33 at the base of leg 16 with the other end being anchored in a peripheral slot 34 pro-

vided with an adjustable set screw 35 threaded through arm 8 of bracket 6. By rotating set screw 35 the tension exerted by spring 32 may be increased or decreased so as to increase or decrease the resistance of slab gate holder 13 to displacement when a slab 5 strikes slab gate 3.

The dimensions of the slot in slab gate 3 may vary depending upon the denier of the yarn running through the same. Slab gate 3 is readily changed for a slab gate having a wider or narrower slot by merely sliding it in an upward direction and out from under fingers 14. A replacement is made by inserting another slab gate under fingers 14 and pressing it home. The width of the slot in slab gate 3 should be sufficient to pass the yarn, without producing any abrasion but should be narrow enough to trip the mechanism when a slab of a size sufficient to be considered a fault is encountered.

It is to be understood that the foregoing detailed description is given merely by way of illustration and that many variations may be made therein without departing from the spirit of our invention.

Having described our invention, what we desire to secure by Letters Patent is:

1. In a yarn slab detector, the combination of a slab gate comprising means adapted to pass a slab-free running yarn and reject a yarn slab, support means for said slab gate, a shaft having said support means pivotally mounted thereon, means, including a ratchet wheel keyed to said shaft and an arm carried by said support means and adapted to operate said ratchet wheel, operatively connecting said pivotally mounted slab gate support means and said shaft for causing any pivotal movement of said slab gate support means on contact with a yarn slab to rotate said shaft, and means operated by the pivotal movement of said slab gate support means for indicating passage of a slab through said slab gate.

2. In a yarn slab detector, the combination of a slab gate comprising means adapted to pass a slab-free running yarn and reject a yarn slab, support means for said slab gate, a rotatable shaft having said support means pivotally mounted thereon, a ratchet wheel keyed to said shaft, an arm integral with said slab gate support means cooperating with said ratchet wheel for translating any pivotal movement of said slab gate support means on contact with a yarn slab into a rotary motion of said shaft, and means operated by the pivotal movement of said slab gate support means for indicating passage of a slab through said slab gate.

3. In a yarn slab detector, the combination of a slab gate comprising means adapted to pass a slab-free running yarn and reject a yarn slab, support means for said slab gate, a rotatable shaft having said support means pivotally mounted thereon, a ratchet wheel keyed to said shaft, means, including an arm integral with said slab gate support means and in register with said ratchet wheel, for translating any pivotal movement of said slab gate support means on contact with a yarn slab into a rotary motion of said shaft, and means operated by the pivotal movement of said slab gate support means for indicating passage of a slab through said slab gate.

4. In a yarn slab detector, the combination of a slab gate comprising means adapted to pass a slab-free running yarn and reject a yarn slab, support means for said slab gate, a rotatable shaft having said support means pivotally mounted thereon, a ratchet wheel keyed to said shaft, means including an arm integral with said slab gate support means and in register with said ratchet wheel, for translating any pivotal movement of said slab gate support means on contact with a yarn slab into a rotary motion of said shaft, a detent cooperating with said ratchet wheel to prevent rotary motion of said shaft in a direction opposite to that caused by movement of said arm, and means operated by the pivotal movement of said slab gate support means for indicating passage of a slab through said slab gate.

5. In a yarn slab detector, the combination of a slab

gate comprising means adapted to pass a slab-free running yarn and reject a yarn slab, support means for said slab gate, a rotatable shaft having said support means pivotally mounted thereon, adjustable stop means cooperating with said pivotally mounted slab gate support means for limiting pivotal movement of said slab gate support means about said shaft, a ratchet wheel keyed to said shaft, means, including an arm integral with said slab gate support means and in register with said ratchet wheel, for translating any pivotal movement of said slab gate support means on contact with a yarn slab into a rotary motion of said shaft, a detent cooperating with said ratchet wheel to prevent rotary motion of said shaft in a direction opposite to that caused by movement of said arm, and means operated by the pivotal movement of said slab gate support means for indicating passage of a slab through said slab gate.

6. In a yarn slab detector, the combination of a slab gate comprising means adapted to pass a slab-free running yarn and reject a yarn slab, support means having said slab gate slidably mounted therein, a rotatable shaft having said support means pivotally mounted thereon, adjustable stop means cooperating with said pivotally mounted slab gate support means for limiting pivotal movement of said slab gate support means about said shaft, a ratchet wheel keyed to said shaft, means, including an arm integral with said slab gate support means and in register with said ratchet wheel, for translating any pivotal movement of said slab gate and slab gate support means resulting from contact with and rejection of a yarn slab into a rotary motion of said shaft, spring means cooperating with said slab gate support means for returning the same to normal operative position after rejection of a yarn slab, a detent cooperating with said ratchet wheel to prevent rotary motion of said shaft in a direction opposite to that caused by movement of said slab gate support means and said arm, and means operated by the pivotal movement of said slab gate support means for indicating passage of a slab through said slab gate.

7. In a yarn slab detector, the combination of a slab gate comprising means adapted to pass a slab-free running yarn and reject a yarn slab, support means having said slab gate slidably mounted therein, a rotatable shaft having said support means pivotally mounted thereon, adjustable stop means cooperating with said pivotally mounted slab gate support means for limiting pivotal movement of said slab gate support means about said shaft, a ratchet wheel keyed to said shaft, means including an arm integral with said slab gate support means and in register with said ratchet wheel, for translating any pivotal movement of said slab gate and slab gate support means resulting from contact with and rejection of a yarn slab into a rotary motion of said shaft, a pointer fixed to said shaft, a scale adjacent to said pointer on which any rotary motion of said shaft is indicated, spring means cooperating with said slab gate support means for returning the same to normal operative position after rejection of a yarn slab by a pivotal movement of said slab gate support means, and a detent cooperating with said ratchet wheel to prevent rotary motion of said shaft in a direction opposite to that caused by movement of said slab gate support means and said arm.
